HUMIDIFIER CASING

Donald D. Allen, Madison, Wis., assignor to Research Products Corporation, Madison, Wis., a corporation of Wisconsin

Filed Dec. 26, 1961, Ser. No. 68,074

Term of patent 14 years

(Cl. D62—4)

Fig. 1.

Fig. 2.

Fig. 3.

FIGURE 1 is a perspective view of the front of the humidifier casing;

FIG. 2 is a top plan view thereof; and

FIG. 3 is a side elevation thereof and taken from the right side of FIG. 1.

The rear, not shown, is open.

I claim:

The ornamental design for a humidifier casing, substantially as shown and described.
